HAT AND HAT-MAKING ART

Ralph K. Reynolds, Danbury, Conn., assignor to
The Mallory Hat Company, Danbury, Conn.,
a Corporation of Connecticut

Application May 9, 1929. Serial No. 361,573

8 Claims. (Cl. 2—194)

This invention relates to hats, and more specifically to felt hats and to an art for making the same.

One of the objects thereof is to provide a hat 5 of novel and attractive appearance. Another object is to provide a hat of the above character in which the material is unweakened and in which the appearance is unchanged by usage. Another object is to provide a simple and practical art for making a hat of the above character. Another object is to provide an art of the above nature characterized by convenience in carrying on and uniformity in results. Other objects will be in part obvious and in part pointed 10 out hereinafter.

The invention accordingly consists in the features of construction, combinations of elements, arrangements of parts, and in the several steps and relation and order of each of the same to 15 one or more of the others, all as will be illustratively described herein, and the scope of the application of which will be indicated in the following claims.

In the accompanying drawing illustrative of 20 certain features of this invention,

Figure 1 is a sectional view of a piece of felt; Fig. 2 is a similar view of the same article at a later stage;

Fig. 3 is a semi-diagrammatic side elevation 25 of a hat and of apparatus used in connection therewith, certain parts being broken away in order to show the construction more clearly;

Fig. 4 is a sectional view of the felt subsequent 30 to the action of the apparatus of Fig. 3;

Fig. 5 is a similar view of the felt at a later stage;

Fig. 6 is a similar view of the same article at a still later stage; and

Fig. 7 is a side elevation of a portion of a 40 completed hat.

Similar reference characters refer to similar parts throughout the several views of the drawing.

Referring now to the drawing in detail, the felt 45 10, as shown in Fig. 1, is preferably, although not essentially, dyed to a shallow depth, as indicated at 11, in a coloring distinctive from that of the body of the felt.

This felt member is understood at this stage 50 to be a portion of an ordinary felt hat in the rough, and it is stretched and blocked prior to the action the results of which are indicated in Fig. 2. To bring this about, the hat is subjected to the action of very coarse sandpaper to "tease" 55 or draw out the long fibers to form a nap as

indicated at 12 in Fig. 2. It may here be noted that the term "nap" is used to denote a surface formed of fibers of substantial length, analogous to the pile of a piece of velvet. The hat is then buffed with wool felt to polish the nap 12 and 60 give it a bright appearance. It is then preferably softened with steam, re-blocked, and, for best results, wet with water, ironed dry, and lured hot.

The hat is then removed from the block, moistened with wet steam, and subjected to the action 65 of the apparatus indicated in Fig. 3 of the drawing.

This apparatus comprises a supporting block 13, heated in any desired manner, as by a steam jacket having in its upper surface a recess shaped 70 to accord substantially with the crown of the hat and provided with a removable brass lining 14 on which is secured, as by soldering, a woven wire fabric 15. This fabric is of a loose mesh, preferably according somewhat in form with 75 the lines indicated at 16 in Fig. 7, later herein referred to. The lining 14, with its inner wire fabric, extends, as at 17, over the top of the block 13, and the inverted hat in the condition above described is fitted therein, as shown in 80 the drawing. If it be desired to produce the effect hereinafter described on the under side of the brim of the hat, there is superposed an annular brass plate 18 provided on its under surface with a registering wire fabric member 19 85 similar in construction to the member 15.

Mounted above the support 13 and adapted to be raised and lowered by any suitable means is a head 20 having on its under surface an expandable bag 21 formed of rubber or the like 90 and adapted to fit within the crown of the hat, indicated as a whole at 22. With the parts in this position, the head 20 is lowered so as to insert the bag 21 within the crown of the hat, and any suitable fluid under pressure is admitted to the interior of the bag 21 to cause it to expand and force the hat 22 into intimate contact with the wire member 15. Simultaneously, the lateral portions of the bag 21, superposed over the brim 95 of the hat, are expanded downwardly by the fluid pressure at the rear thereof and compress the brim, subjecting the felt at that point to embossing action by the wire members which it contacts.

This pressure is maintained a sufficient length 100 of time to permanently emboss the form of the wire fabric into the surface of the felt. The result of this action is diagrammatically indicated on an enlarged scale in Fig. 4 of the drawing, 110 in which the depressions 23 correspond in form

and contour to the various wires against which the felt is forced.

The hat is then removed from the apparatus above described and is blocked. The hat is then 5 subjected to a pouncing action with very fine sandpaper while rotated at high speed, as, for example, 2500 revolutions per minute. This action may be performed by hand or with a suitable automatic pouncing machine. This cuts off 10 the outermost surface of the felt, thus removing the relatively raised portions and leaving the felt as indicated in Fig. 5 of the drawing. In this form, the majority of the surface of the felt is cut down to the body, as indicated at 24, thus 15 removing on such portions the nap or long fibers 12, and, if dyeing be employed, the thin layer of dyed felt.

At this stage, the hat may, if desired, be ironed and lured.

20 The hat is then moistened again with wet steam and subjected to the action of the apparatus indicated in Fig. 3 with the parts 14 and 18 and their accompanying wire members removed. The result of this action is to press the 25 felt flat, as indicated in Fig. 6 of the drawing, the outline of the wire fabric being then represented by lines of long fiber, as indicated at 25, springing from lines of felt of distinctive color if the shallow dyeing feature be employed.

30 The completed hat, as indicated in Fig. 7 of the drawing, presents an exposed surface in which there is formed thereon an outline similar to that of loose fabric. This outline is formed by the lines 25 of long fiber, and preferably of felt 35 of distinctive color. The hat is thus given a novel appearance which is distinctive and attractive. Furthermore, it retains this appearance under conditions of hard use.

40 As many possible embodiments may be made of the mechanical features of the above invention, and as the art herein described might be varied in various parts, all without departing from the scope of the invention, it is to be understood that all matter hereinabove set forth 45 or shown in the accompanying drawing is to be interpreted as illustrative and not in a limiting sense.

I claim:

50 1. The hat-making art, which consists in blocking a hat, subjecting the outer surface of the felt to coarse abrasive action to draw out long fibers or nap, buffing said felt to polish said nap, softening the hat with steam, wetting the hat, ironing the hat dry, wetting the hat 55 again, pressing the outer surface of the hat against a member of predetermined form to emboss in its outer surface a predetermined design, and subjecting the outer surface of the felt to fine abrasive action to remove the nap at all 60 portions other than those depressed by said embossing action.

65 2. The hat-making art, which consists in blocking a hat, subjecting the outer surface of

the felt to coarse abrasive action to draw out long fibers or nap, buffing said felt to polish said nap, softening the hat with steam, wetting the hat again, pressing the outer surface of the hat against a member of predetermined form to emboss in its outer surface a predetermined design, subjecting the outer surface of the felt to fine abrasive action to remove the nap at all portions other than those depressed by said embossing action, and pressing the outer surface of the felt against a smooth surface. 80

85 3. The hat-making art, which consists in blocking a hat, subjecting the hat to coarse abrasive action to draw out from the felt long fibers to form a nap thereon, then depressing the nap beneath the outer surface of the felted portion of the hat body at selected places to form a predetermined design, and then removing the nap from the undepressed portion of the felt. 90

95 4. The hat-making art, which consists in blocking the hat, drawing out long fibers of the outer surface of the felt to form a nap thereon, polishing said nap, and depressing the nap beneath the outer surface of the felted portion of the hat body at selected places to form a predetermined design. 100

105 5. The hat-making art, which consists in blocking the hat, drawing out long fibers of the outer surface of the felt to form a nap thereon, polishing said nap, depressing said nap beneath the outer surface of the felted portion of the hat body at selected places to form a predetermined design, and removing the nap from the undepressed portion of the felt. 110

115 6. The hat-making art, which consists in blocking a hat, subjecting it to coarse abrasive action to draw out long fibers or nap, polishing said nap, wetting the hat, depressing the nap beneath the outer surface of the felted portion of the hat body at selected places to form a predetermined design, and subjecting the hat to a fine abrasive action to cut away the nap from portions undepressed. 120

125 7. The hat-making art, which consists in blocking a hat, subjecting the felt of the hat to coarse abrasive action to draw out long fibers thereon, pressing said felt having the nap against a member formed in the design of a fabric thus to depress portions of the nap beneath the outer surface of the felted portion of the hat body to transfer said design to the hat body, and removing said nap on the portions of said felt undepressed by said member. 130

135 8. A hat formed of felt having a substantially smooth outer surface, portions of felt of characteristics different from the felt constituting the greater area of the hat extending a substantial distance below said outer surface, and long nap extending upwardly from said portions, the remainder of the hat surface having no nap. 140
